CLAIM

The ornamental design for a lighting fixture, as shown and described.

DESCRIPTION

FIG. 1 is a front right perspective view from below of a lighting fixture according to the new design;

FIG. 2 is a front, right perspective view from above thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof;

FIG. 9 is a front right perspective view from below of an alternative embodiment of the lighting fixture having translucent surfaces according to the new design;

FIG. 10 is a rear, right perspective view from above thereof;

FIG. 11 is a front elevational view thereof;

FIG. 12 is a right side elevational view thereof;

FIG. 13 is a left side elevational view thereof;

FIG. 14 is a rear elevational view thereof;

FIG. 15 is a top view thereof; and,

FIG. 16 is a bottom view thereof.

The broken lines in the drawings illustrate portions of the lighting fixture that form no part of the claimed design.

The stippling shown in FIGS. 9-16 represent translucent surfaces of the design and does not represent texture or surface ornamentation.

The long dash-short dash lines in the drawings represent a boundary of the claimed design and form no part of the claimed design.
